(57) **CLAIM**

The ornamental design for a clipper, as shown and described.

DESCRIPTION

FIG. 1 is a perspective view of a clipper showing our new design;

FIG. 2 is a front view of the design shown in FIG. 1;
FIG. 3 is a back view of the design shown in FIG. 1;
FIG. 4 is a left side view of the design shown in FIG. 1; the right side view being a mirror image thereof;
FIG. 5 is a bottom view of the design shown in FIG. 1; and, FIG. 6 is a top view of the design shown in FIG. 1.
The broken lines shown in the drawings illustrate the environment and form no part of the claimed design.
